SASH BALANCE

Clifford T. Carnes, Charles F. Steffes, Edward N. Wright, and John E. Comer, Los Angeles, Calif.

Application June 1, 1938, Serial No. 211,192

3 Claims. (Cl. 16—198)

This invention, a sash balance, is designed for the control of all types of vertically-sliding sash and similar devices, such as doors which are vertically or inclinably slidable and which are required to be retained in various adjusted positions.

The usual type of sash balance, consisting of sash cord and weights, require considerable space back of the side members of the frame, or in the wall, for free movement of the weights. The installation must be made when the window frames are being installed and completed only when the sash is installed in the frame. They are adjustable only by actual changing of the weights to lighter or heavier types. The sash cord for the lower sash is always in full view when the sash is closed or partly open, and the cord for the upper sash is in full view whenever the upper sash is partly opened, presenting an unsightly appearance. These cords become soiled and consequently more unsightly and unsanitary with age, and are very efficient collectors of dust and dirt.

Other types, such as friction shoes, operate with restraint when the frame is new, and, after the shoe has worn a smooth track on the frame, they fail to function properly.

It is to overcome all of the above undesirable features that this invention is developed, and its particular advantages reside in the fact that the entire balance mechanism is completely concealed with any adjusted position of the sash, leaving the visible portions of the slide ways in the frame between the stops clear and free of cords or marring by friction shoes, permitting the surfaces of the frame to be kept in an unmarred, dustless and unobstructed condition; and also in the fact that the balance can be completely installed and adjusted at the time of manufacture of the sash, and can thus be delivered on the job complete, requiring only the attachment of the end of the cable, when the cable type is used, to the frame, which is provided with a suitable catch already installed; and in the case of the rack and pinion type, the connection is automatically made when the stop is attached to the frame.

Therefore, in the installation of window frames and sash, no space is required between the walls and no installation or fitting is required on the job.

If for any reason adjustment should be desired after installation, the sash balance is easily removed and replaced, and just as easily adjusted.

In describing the invention, reference will be made to the accompanying drawing, in which;

Fig. 1 is a fragmentary front view of a sash, shown partly in section to expose a sectional view of the invention installed therein, the section corresponding to a line 1—1 of Fig. 2.

Fig. 2 is an end view of the lower portion of Fig. 1, showing the invention in end elevation.

Fig. 3 is a section taken on line 3—3 of Fig. 1.

Fig. 4 is a modified form of the invention shown fragmentarily.

Fig. 5 is another modified form of the invention.

The invention is installed as illustrated in Figs. 1 and 2, and consists of a spring barrel 10 having an inturned flange 11 formed at one end, and a sheave housing 12 formed integral with or attached to, the other end of the spring barrel, and this housing terminates in a plurality of ears 13 or other means for securing the sheave housing to the stile plate 14.

The stile plate 14 is provided with suitable slots 15 to receive the ears 13, and the plate is depressed as indicated at 16 to retract the ears when clinched to the plane of the plate.

A shaft bearing 17 is formed in the stile plate in axial relation to the circular series of slots 15 and supports one end of a shaft 18, the other end of which shaft is supported in an axial passage formed in the adjusting plug 19 which is rotatably fitted in the spring barrel as shown, and which is provided with removable securing means, such as a pin 20 which passes chordally through the spring barrel and plug. A screw driver slot 21 is provided at the outer end of the plug for purposes of adjustment of the tension of the spring.

A sheave 23 is mounted on the shaft and located within the sheave housing 12, and may operate freely on the shaft, but is shown as pinned thereto as indicated at 24.

A spiral spring 25 has one end secured to the sheave as indicated at 26, and its other end is secured to the plug or adjuster 19 as indicated at 27.

A cable 28 has one end attached to the sheave 23 as indicated at 29 and its other end attached to the window frame 30 at a point preferably just below the top 31 of the sash when the sash is in its lowered position for the lower sash and upper sash, both, as indicated at 32, and this cable preferably consists of a thin cable, such as airplane strand, which with ordinary sash permits the use of a cable about $\frac{1}{16}$ inch in diameter, depending on the weight of the sash, and whether

one balance is used, or whether one is used for each end of the window or sash.

A passage 33 is formed in the sheave housing for free passage of the cable 28, and a passage 34 5 is formed in the stile plate 14 by slitting and bending back a portion 35 of the plate to coincidentally form a smooth guide or roll edge 36 for the cable.

The plate is formed of resilient metal and the 10 lower end is slit upwardly as indicated at 37, and the intervening portion is bent outwardly as indicated at 38 and inwardly at its lower end to form urging or spacing means to urge or maintain the lower end of the sash against the other side 15 of the window frame to prevent cocking of the sash, in other words, to maintain vertical alignment of the sash.

A loop, or other attaching means is formed at the terminal end of the cable, as at 32, and when 20 the balance is installed in the sash at the time of manufacture or at any other time, a keeper (not shown but well known) is removably placed in the loop which is thus prevented from passing through the slot 34, so as to maintain the adjustment of the spring.

To adjust the balance, it is merely necessary to 25 remove the pin 20 and turn the plug head 22 with a screw driver or wrench until the proper tension is secured in the spring, and re-insert the pin 20. The tension is readily measured by 30 anchoring the sash balance and attaching the cable loop to the hook on a spring balance, and the adjustment can be carried out until the spring balance indicates the proper pull to suit 35 the particular weight of the sash.

For twin use, the shaft ends are preferably 40 slotted as indicated at 40 to receive the pins 24, thereby facilitating assembly, the stile plates being applied after the adjustments are made. 45 Even if the springs are adjusted differently, they can have no effect on the uniform and non-cocking operation of the sash.

In Fig. 4 the entire structure is identical to that 45 just described, except that the sheave 23 is replaced by a pinion 41, and this pinion meshes with a rack 42 which is imbedded or installed in one of the stops 43 forming the guides for the sash; thus the pinion and rack is merely substituted for the sheave and cable.

In Fig. 5, the spring 44 of the clock-spring 50 variety is wound within the sheave 45, this unit displacing the sheave 23, and may be used alone or with several of these drums and springs cumulatively connected in series or in conjunction with the spring 25, spring barrel 10 and adjuster 19, and stile plate 14.

By making the spring 25 with a suitable number 55 of coils, the tension will remain sufficiently uniform in all adjusted positions of the sash for convenient operation.

It will be understood that variations in construction and arrangement of parts, which vari-

ations are consistent with the appended claims, may be resorted to without detracting from the spirit or scope of the invention, or sacrificing any of the advantages thereof.

We claim:

1. A sash balance comprising; a spring barrel having a sheave housing associated with one end; an adjusting member mounted for rotational adjustment at the other end, and an axial passage formed in said adjusting member; a stile plate 10 mounted on said sheave housing and having a bearing formed in coaxial relation to said axial passage; a shaft supported in said bearing and axial passage; a sheave mounted on said shaft adjacent to said bearing; a spring encompassing said shaft and having its respective ends connected respectively to said adjusting member and to said sheave; means for securing said adjusting member in adjusted position and means for adjusting said member; a cable passage formed 15 through said stile plate and through said housing, and a cable having one end attached to said sheave and passing through said cable passages and its other end arranged for attachment to the side member of a window frame.

2. A sash balance comprising; a spring barrel 25

inwardly flanged at one end and a sheave housing coaxially associated with the other end; an adjusting member rotatably adjustable in said one end and having an axial bore and means for adjusting the member, and means for securing said member against rotation relative to said spring barrel; a stile plate secured to the end of said housing and having a bearing in axial alignment with said bore; a shaft having supports in said bearing and in said bore; a sheave mounted on said shaft within said housing; a spring having 30 its respective ends secured to said adjusting member and to said sheave; a cable passage formed in said housing and through said plate; and a cable attached to said sheave and windable thereon and passing through said cable passages and having means formed at its other end 35 for attachment to a window frame.

3. A sash balance having a shaft and a spring 45

for rotatably urging said shaft; a sheave housing, and a stile plate forming a cover for said sheave housing; a sheave mounted on said shaft within said sheave housing, and a cable having one end secured to said sheave and windable 50 thereon and passing through passages formed through the peripheral wall of said sheave housing and through said stile plate; said cable extending upwardly between the sash and the window frame in which the sash is mounted and 55 having its other end attached to the window frame.
